BOUNDARY MARKER

Axel S. Carlson, New York, N. Y.

Application October 20, 1945, Serial No. 623,539

4 Claims. (Cl. 72—7,3)

1

This invention relates to markers, more particularly to a boundary marker. While my marker may be adapted to any use where a boundary marker is desired, it is particularly adapted to marking corners of cemetery plots. In most of the newer cemeteries, gravestones and other objects which extend above the ground are forbidden, first, for the general appearance of the cemetery and, secondly, they interfere with the proper maintenance, the cutting of grass and general landscaping. It is customary, therefore, to mark the corners of the plots with a stone sunk into the ground so that its top would be level with the surface. However, during the winter time when snow is on the ground it becomes most difficult to locate the plot even with the use of a map or chart and where the owners wish to visit the plot or place where it is necessary to have a burial the snow must be scraped from a considerable area before the plot can be located. This is obviously inconvenient and expensive.

An object of this invention is to provide a boundary marker, which when not needed may be set flush with the ground, but which when it is so desired may be pulled upward and positioned a desired distance above the ground so that it will extend above the snow and make the location of the marker easy.

A further object of my improved marker is that it is possible to drop it flush with the ground in order to cut the grass or during the clear season when it is not needed and then in the fall it would be a simple matter to raise the marker's shaft upwardly so that it can be easily located.

Other objects and advantages of my invention would be apparent in the accompanying drawings, in which

Fig. 1 is a cross-sectional view of a preferred form of my invention.

Fig. 2 is a plain view thereof.

Fig. 3 is a modified form of my invention shown in cross-sectional elevation.

Fig. 4 is a plain view thereof.

Fig. 5 is a cross-sectional view taken on the line 5—5 of Fig. 3.

Fig. 6 is a partial enlarged sectional view of the upper portion of the device shown in Fig. 3.

Referring more particularly to the drawings in Figs. 1 and 2, I provide a marking or boundary stone 10 provided with a vertical elongate well 15 and an upper passage 15' of reduced diameter connecting the well 15 with the upper surface of the stone. The upper surface of the

stone 10 is marked into segments A, B, C, and D, and with boundary lines 11, 12, 13 and 14 separating said sections. The corner stone 10 may be of concrete or any suitable material, and is preferably sunk flush with the surface of the ground 16. Mounted in the passage 15' snugly is a sleeve 17 having bayonet slots 18 at its lower end and on opposite sides thereof. The shaft 15 may be solid, or as shown, may be hollow, and is provided with a tight fitting plug 19 at the top thereof which has a collapsible handle 20. At the lower end of the shaft 15 are pins 21 oppositely disposed and adapted to cooperate with the bayonet slots 18. A cup-shaped plate 22 is disposed in a recess in the top of the stone above the top of the sleeve 17. The shaft 15 is disposed within the sleeve 17 and a flange 23 on the plug 19 supports the shaft by resting on the bottom of the cup-shaped plate 22 as shown in Fig. 1.

When it is desired to move the marker shaft 15 to the upward position, it is merely necessary to lift up on the handle 20 until the shaft 15 is in an upward position and then rotate the said shaft until the pins 21 are disposed in the bayonet slots 18, whereupon the shaft will be retained in this upward position. In the modified form shown in Figs. 3 to 6 inclusive, the stone 30 is provided with a well 31 connected by a passage 31' of reduced diameter to the top of the stone and opening into a recess 33 which in its preferred form is shown as saucer-shaped. Beneath this recess is an annular drain 34. The shaft 35 disposed within these passages and adapted to be moved up and down therein is provided with lateral notches 36 and 37 formed at spaced levels thereon. The notch 37 is disposed immediately below the head 38 of the shaft. Within the stone, and aligning the reduced passage 31', is a sleeve 39 extending upwardly therein from the well 31. The sleeve 39 abuts the underside of the washer 32 at one side 40, but is longer and abuts the inner end of washer 32 at a side opposite the one side as indicated by 41.

There is a latching element 32 which in its preferred form is saucer-shaped, and in its bottom is provided with an eccentric hole through which the shaft 35 extends. The shape of the recess 33 and the latching element 32 is such that as the latching element moves into its recess, it tends to assume a position wherein the hole in the bottom thereof will tend to assume its normal eccentric position with respect to the shaft. This full eccentric positioning of the latching element, however, can not be assumed by it until

one or the other of the notches 36 and 37 are presented in a plane co-incident with the bottom of the latching element. When this happens, the latching element becomes fully seated as shown in Figs. 3 and 6, and the shaft is held in this predetermined position.

In the operation of this form of the device, and assuming the parts in the position shown in full line in Fig. 3, the latching element is fully nested on its seat, and one edge of the hole engages the notch 37 to hold the shaft 35 in the position shown. It will be noted that the top of the head 38 of the shaft is at this time flush with the top of the stone 30. When it is desired to elevate the shaft for the purpose of more definitely marking the boundary, it is merely necessary to grasp the head 38 and pull up on the shaft 35. This will temporarily cause the latching element 32 to be lifted with the shaft, but a slight lateral manipulation of the latching element as shown by arrows in Fig. 3 will release it from engagement with the notch 37 and cause it to drop by gravity along the shaft and to at least partly enter its seat or recess 33. As the shaft is lifted to bring the lower notch 36 just above the top of sleeve 39, the latching element will, by gravity, move into full nesting position within its seat to dispose its aperture in eccentric relation with the shaft and with one edge lying in the notch 36, thus holding the shaft in its elevated position. When it is desired to lower the shaft, it is merely necessary to raise it slightly and manipulate the latching element laterally to release it from engagement with the notch 36 whereupon the shaft may be lowered until its notch 37 comes into alignment with the hole in bottom of the latching element whereupon the parts will reassume their latching relation shown in full lines of Fig. 3. A rim or flange 42 is provided at the bottom of the shaft 35 to prevent its complete removal from the stone.

It will be seen that I have provided a simple, inexpensive, but highly efficient marker, which may be readily operated and simply moved from the inoperative to the operative position. It will be appreciated that this will save considerable time and inconvenience in locating boundary lines and at the same time when not needed can be dropped out of sight.

I claim:

1. A boundary marker including a stone having a well therein and a recess at the top thereof having downwardly and inwardly sloping walls into which said well opens, a shaft disposed within said well, the dimensions of said shaft being such that there is a snug sliding fit between said shaft and the upper portion of said well, said shaft being adapted to be moved axially of said well, said shaft having laterally extending vertically spaced notches, and a disk-shaped latching element in engagement with and supported by said recess having an elongated opening therein, said latching element being movable away from said recess, said shaft being disposed within said opening, a portion of said latching element adjacent said opening being received by one of said notches when said latching element is fully seated in said recess, the dimensions of said opening in said latching element, said notches and said latching element being such that said portion of said latching element can be moved out of said one of said notches when said latching element is moved away from said recess.

2. A boundary marker including a stone having

a well therein and a recess of predetermined shape at the top thereof into which said well opens, a shaft disposed within said well in such manner that there is a snug sliding fit between said shaft and the upper portion of said well, said shaft being adapted to be moved axially of said well and having laterally extending vertically spaced notches thereon, and a latching element of the same shape as said recess having a rim defining an elongated hole therein movable into and out of engagement with said recess, said shaft being disposed through said hole, and the dimensions of said notches, said shaft and said rim being such that said rim is movable into and out of engagement with each of said notches when said latching element is moved away from seated position in said recess.

3. A boundary marker including a stone having a well therein and a recess of predetermined shape at the top thereof into which said well opens, a shaft disposed within said well in such manner that there is a snug sliding fit between said shaft and the upper portion of said well, said shaft being adapted to be moved axially of said well and having laterally extending vertically spaced notches thereon, and a latching element having an elongated opening therein movable into and out of seated engagement with said recess, said shaft being disposed within said opening, a portion of said latching element adjacent said opening being received by one of said notches when said latching element is fully seated in said recess, said recess having inwardly and downwardly sloping walls, and said latching element having complementary sloping surfaces so that said latching element will tend to seat in said recess upon movement of said latching element into said recess.

4. A boundary marker including a stone having a well therein and a recess of predetermined shape at the top thereof into which said well opens, a shaft disposed within said well in such manner that there is a snug sliding fit between said shaft and the upper portion of said well, said shaft being adapted to be moved axially of said well and having laterally extending vertically spaced notches thereon, and a latching element of the same shape as said recess and having an elongated opening therein movable into and out of seated engagement with said recess, said shaft being disposed within said opening, a portion of said latching element adjacent said opening being received by one of said notches when said latching element is fully seated in said recess, the dimensions of said latching element, said opening and said portion being such that said latching element may be moved lateral to the axis of said shaft when said element is not fully seated in said recess so as to move said portion out of said one of said notches.
